Primary Examiner—Ruth McInroy*Attorney, Agent, or Firm*—Ancel W. Lewis, Jr.[57] **CLAIM**

The ornamental design for a heat reduction volume compensator with center hole for disposition between a coffee pot and hot plate, as shown and described.

DESCRIPTION

FIG. 1 is a top perspective view of a heat reduction volume compensator with center hole showing my new design;

FIG. 2 is a top plan view of FIG. 1;

FIG. 3 is a bottom plan view of FIG. 1;

FIG. 4 is a side elevational view of FIG. 1;

FIG. 5 is a sectional view taken along line 5—5 of FIG. 2;

FIG. 6 is a top perspective view of a second embodiment of the design of FIG. 1;

FIG. 7 is a top plan view of FIG. 6;

FIG. 8 is a bottom plan view of FIG. 6;

FIG. 9 is a side elevational view of FIG. 6; and,

FIG. 10 is a sectional view taken along line 10—10 of FIG. 7.
